UNITED STATES PATENT OFFICE.

VALENTINE F. BOEHM, OF CHICAGO, ILLINOIS.

BEER COOLING AND PURIFYING APPARATUS.

No. 882,862.

Specification of Letters Patent. Patented March 24, 1908.

Application filed December 17, 1906. Serial No. 343,384.

To all whom it may concern:

Be it known that I, VALENTINE F. BOEHM, a citizen of the United States, and a resident of Chicago, in the county of Cook and State 5 of Illinois, have invented certain new and useful Improvements in a Beer Cooling and Purifying Apparatus, of which the following is a full, clear, and exact description.

My invention relates to the means employed in saloons for cooling and purifying draft beer, and its object is, first, to keep the beer in a perfectly pure and wholesome condition; second, to avoid the possibility of the gas, air and foam being expelled from the 15 same faucet from which the beer is drawn; third, prevent the beer becoming contaminated by the chemical reaction resulting from its standing in metallic pipes for any considerable length of time; fourth, enable 20 the bar-tender to remove the dross and surface impurities from the beer when a fresh barrel or keg is opened, and also drain the concentrates and sediment from the bottom of the keg or barrel when the same is about 25 exhausted, and fifth, to provide for the expeditious and thorough cleansing of the apparatus, substantially as hereinafter fully described and as particularly pointed out in the claims.

30 In the drawings:—Figure 1 is a vertical longitudinal section through my improved apparatus. Fig. 2 is a vertical transverse section taken on dotted line 2—2, Fig. 1. Fig. 3 is a side elevation of a modified form 35 of the reservoir of the same. Fig. 4 is a detail view of an automatic blow off which can be used in connection with my invention, if desired.

In the drawings A represents a rectangular 40 or other suitably shaped box or receptacle in which my improvements can be conveniently placed and packed in broken ice or other cooling medium; and B represents a reservoir which has, as shown in the drawings, a 45 substantially cylindrical shaped body with rounded ends, and is supported above the bottom of the box A by suitable legs a, a. This reservoir B may be of any other shape desired, so long as its construction is such as 50 to permit its use in connection with the other features of my invention, hereinafter fully described.

At about its center of length the reservoir B is provided with an inlet tube b, which 55 enters its bottom and is connected at its lower end to a horizontal pipe or tube C,

one branch of which extends, preferably, out through the rear of the cooling box to a stop-cock c, which is connected to the pipe or tube D leading to the beer barrel or keg. 60 The other branch of the pipe or tube C extending in the opposite direction from the inlet tube b, extends out through the front of the box and terminates in a faucet E, which may be connected directly to the 65 front of said box or some other part of the bar-fixtures, according as desired. The reservoir B is provided with a gas and air vent which, preferably, consists of a tube d connected to and leading from its top, which 70 extends to the front of the box, where it terminates in a suitable vent-cock F, which latter, like the faucet E, may be connected directly to the front of the box A or to some other part of the bar fixtures. At about its 75 center of height the reservoir is provided with a discharge pipe or tube G, which, as shown in the drawings, extends from one end of the reservoir to the front of the box, where it is provided with a faucet g. If desired this outlet pipe or tube might extend through a suitable packed opening in the front of the box and lead to and be connected with a faucet g connected thereto or to any other part of the bar fixtures within convenient reach of the bar-tender. 80

I prefer to make the reservoir B; the tube or pipe C; the tube or pipe d, and the outlet pipe or tube G of glass, although it would be possible to make these parts of some suitable 90 enameled ware, or, even of metal, although I prefer, if possible, to avoid the use of the latter, except where the connections and fittings, it may be necessary to use in connection with the apparatus, are concerned. 95

After the apparatus has been cleansed by attaching a water supply hose to cock F and permitting the water to flow therethrough into the reservoir B and out through the faucet E, I close cock F and faucet E, and 100 open the stop-cock c, and thus permitting the beer to flow through pipe C into the reservoir sufficiently to carry the dross and surface impurities from the barrel, whereupon the stop-cock c is closed, and said dross and impurities are drained from the apparatus out through faucet E. Closing the faucet E again, I again open the stop-cock c, and this time permit the beer to flow into 105 and fill the reservoir B until the gas and air in the upper part of the reservoir creates a back pressure sufficient to prevent the fur-

ther accumulation of beer therein, whereupon I open the vent cock F and allow the escape of said gas, air and foam and the pure beer to completely fill the reservoir until it begins to flow from said vent-cock. The vent-cock is then closed, and the apparatus is then in condition to permit of the pure beer being drawn from a point in the reservoir, where the beer will always be in a pure condition, 10 namely, above the point where any possible sediment may collect, and below the point where foam or gas or air may accumulate. When the barrel or keg of beer is practically exhausted, the sediment and residual beer, 15 which may be more or less cloudy and concentrated, can be drawn off through the faucet E, and after this is done, the apparatus can be washed in the manner hereinbefore explained, and made ready for a fresh keg 20 or barrel.

If desired, instead of the vent tube d and cock F, some automatic blow-off for the escape of the air and gas from the reservoir may be provided, similar to that in use in 25 connection with steam boilers and generators, substantially as shown in Fig. 4 of the drawings, in which the gas outlet tube h is provided at its upper end with a suitable metallic rim j, the exit opening of which provides a valve-seat, that is closed by a valve H, secured to a lever I, which latter is fulcrumed at one end between lugs arising from the said rim, and extends diametrically across the mouth of said outlet-pipe, and is 30 provided with a suitable adjustable weight J at the other end.

In Fig. 3 I show a modified form of my invention in which the reservoir K is shown as inclined upwards from the lowermost point, 40 where it is connected by means of the inlet-tube k to the intake pipe or tube L. This modified form of reservoir dispenses with the vent-cock d, or automatic blow-off shown in Fig. 4 of the drawings, and is provided with a 45 tapering discharge opening M, the upper side of the approach of which is so shaped as not to leave a shoulder to the reservoir in which gas or air or foam may collect, thus reducing to a minimum the surface area of the beer 50 within the reservoir above which foam or gas

or air may collect. In this modified form of reservoir, the initial accumulation of gas, air and foam is drawn off through any suitable discharge-pipe, (not shown), after which the beer, after a very slight discharge of foam, 55 will flow pure from the reservoir.

I do not desire to be confined in the use of my improved apparatus to the sale of draft beer, as it is possible and indeed in some instances desirable for use in connection with 60 soda fountains. All such adaptions of my invention, together with all slight modifications in the shape of the reservoir, or in the construction of the fixtures and connections used in conjunction therewith, I desire to be 65 understood as contemplated within the scope of my invention.

What I claim as new is:—

1. An apparatus for purifying and cooling beer comprising a suitable receptacle, a supply-pipe extending directly and entirely through said receptacle, a reservoir above said supply-pipe having communication therewith, a valve-controlled exit for said supply-pipe outside of said receptacle, and 70 an outlet-pipe connected to said reservoir above its bottom and provided with a valve-controlled exit.

2. An apparatus for purifying and cooling beer comprising a suitable receptacle, a 80 valve-controlled supply-pipe extending directly and entirely through the same, a reservoir above said supply-pipe, a pipe leading from the bottom of said reservoir and connected to said supply-pipe mediate the ends 85 thereof, a valve-controlled exit for said supply-pipe outside of said receptacle, an outlet-pipe connected to said reservoir above its bottom and provided with a valve-controlled exit outside of said receptacle, and a vent 90 leading from the top of said reservoir and provided with a valve-controlled exit outside of said receptacle.

In testimony whereof I have hereunto set my hand and seal this 14th day of December, 95 A. D., 1906.

VALENTINE F. BOEHM. [L. s.]
